UNITED STATES PATENT OFFICE.

JACOB SUTER JAMMER, OF CUMBERLAND, MARYLAND, ASSIGNOR TO WESTERN ELECTRIC COMPANY, INCORPORATED, OF NEW YORK, N. Y., A CORPORATION OF NEW YORK.

MULTIPLEX TRANSMISSION.

Application filed December 17, 1924. Serial No. 756,399.

This invention relates to wave transmission systems and is particularly adapted for use in attenuation compensating or equalizing circuits such as are frequently employed in multiplex carrier current signaling systems.

An object of the invention is to provide for controlling the transmission characteristic of a transmission line or system in an economical and efficient manner.

A related object of the invention is to compensate for the unequal attenuation of the different waves in the transmission medium of a multiplex signaling system.

Another object of the invention is to reduce the requirements on the grouping filters employed at repeater points or elsewhere in multiplex signaling systems.

The invention is adapted for use in multiplex carrier current telephone and telegraph systems operated on a group frequency basis, wherein the different channel frequencies for transmission in one direction are grouped in a different frequency range from that employed for transmission in the opposite direction.

In multiplex systems of this type, due to the inherent attenuation of the transmission line and its associated apparatus, it is frequently necessary to amplify the transmitted waves. This may be accomplished by inserting two-way repeaters at intervals along the transmission line, so arranged that all of the waves transmitted in one direction will be amplified in one branch of the repeater and all the waves transmitted in the opposite direction will be amplified in another branch of the repeater.

In such systems, particularly those employing long line conductors, it is well known that the waves of higher frequencies are less efficiently transmitted than those of lower frequencies. The wider the range of frequencies transmitted, the greater is the distortion due to the poorer transmission or greater attenuation of the high frequencies relative to the low.

If a repeater of the above type is used for a wide range of frequencies on a line possessing unequal attenuating properties, it is desirable to associate with the repeater some means for equalizing or compensating for the distortion due to such attenuation. This is desirable in order that the repeater

amplifiers may amplify all of the waves to the same output level. In general, it is desirable to introduce the means of correction for the line attenuation at the repeater, since the correcting means introduces a loss which may be made up by the repeater.

Heretofore, to meet these requirements, it has been customary to so design the repeater grouping filters as to offer a minimum attenuation to the frequencies included within the transmission range of the filters, and then, in order to equalize the load on the input of the repeater amplifier, an equalizing network had been inserted between the input filter and the amplifier. A system of this type is shown in U. S. Patent No. 1,413,357 to P. A. Raibourn, issued April 18, 1922.

When for economic reasons it becomes necessary to secure a maximum number of communication channels by reducing the frequency spacing between the oppositely directed groups of frequencies, repeaters of the above type are expensive to construct. This is due not only to the cost of the separate attenuation equalizers, which is an important item in itself, but also, as herein-after more fully explained, because of the severe requirements imposed upon the repeater grouping filters.

According to a feature of this invention, the attenuation requirements for equalizing the load on a repeater amplifier are met by the grouping filter due to its novel mode of construction, thus doing away in some instances, at least, with the necessity for separate attenuation equalizing networks, and at the same time reducing the attenuation requirements on the grouping filters.

The invention will be described as applied to a two-way amplifying repeater for use in multiplex carrier current telephone or telegraph systems, but it is to be understood that it may also be applied to other places in the system than at repeater points, and to various types of systems other than multiplex carrier systems.

The various features and objects of the invention will appear from the following description and the accompanying drawing, in which:

Fig. 1 is a diagrammatic illustration of a two-way amplifying repeater constructed in accordance with the invention.

Fig. 2 shows curves illustrating the principle of operation of the repeater of Fig. 1.

Fig. 3 illustrates the type of high pass filter which may be employed in the system of Fig. 1 in carrying out the invention.

Fig. 4 shows curves illustrating the characteristics of the filter shown in Fig. 3 depending upon the time constant of the coils employed therein.

The two-way repeater of Fig. 1 comprises two one-way repeating channels RW and RE, adapted to connect transmission line sections W and E.

The currents incoming at the repeater from line section E are amplified in the channel RE and the amplified currents are delivered to line section W. Similarly, the currents incoming from line section W are amplified in the channel RW and the amplified currents are delivered to line section E.

The currents incoming from the line section W are of higher frequencies than those incoming from line section E. The respective repeater channels are provided with frequency discriminating filters which direct the incoming currents to the proper channels.

The repeater channel RW includes a high pass input filter HPIF, an amplifying structure WA and a high pass output filter HPOF. The repeater channel RE includes a low pass input filter LPIF, an amplifying structure EA and a low pass output filter LPOF.

The amplifying structures WA and EA may be of any well-known type such, for example, as that disclosed in the Raibourn patent, *supra*.

The directional filters HPIF and HPOF are designed to transmit currents of the upper group of frequencies to be repeated by the amplifying structure WA and to suppress from transmission currents of lower frequencies, while the directional filters LPIF and LPOF are designed to transmit currents of the lower group of frequencies to be repeated by the amplifying structure EA and to suppress currents of higher frequencies.

These filters may be of the general type disclosed in United States patent to G. A. Campbell, No. 1,493,600, dated May 13, 1924, and may be of the particular composite wave filter type discussed in Part III of an article on the "Theory and design of uniform and composite electric wave-filters" by Otto J. Zobel, in the Bell System Technical Journal of January, 1923. These filters consist in general of a plurality of sections having series and shunt reactances designed, according to well known laws, for the range of frequencies of the currents which the filters are to transmit.

Since the attenuation of a transmission line is a function of the frequency, the carrier currents incoming at the repeater will vary in magnitude corresponding to the attenuation of the line which they have traversed. It is likewise evident that when these currents are passed through the repeater channels RW or RE, as the case may be, to the succeeding line, the variations in magnitude in the second line will be proportionally much greater than for the first line unless means are included in the repeater channels for the purpose of effectually decreasing the amplification of the amplifying structures WA and EA for the lower or less attenuated frequencies.

According to the invention, both functions of discriminating against the frequencies which it is desired to suppress from transmission and of furnishing the equalization required for the different carrier frequencies which the respective filters are designed to transmit are performed in certain cases by one and the same network thus dispensing with the second network heretofore thought necessary, together with its high cost of construction.

This is accomplished by a novel mode of construction in the high pass filter. The invention is particularly applicable to the construction of high pass filters HPIF and HPOF since it happens that the gradual cut-off obtained by the cheaper design in accordance with the invention is in the right direction in the case of the higher grouping filters to aid in the attenuation equalization. The expense of such a repeater may thus be materially reduced by constructing the high pass filters in accordance with the invention. The low pass filters LPIF and LPOF, may be constructed as heretofore in the art.

Fig. 2 shows graphically the transmission requirements to be met at a repeater point on a typical carrier line in order to compensate for the unequal line attenuation over the two groups of frequencies. In this figure the transmission loss is plotted against frequency.

The curve *a*—*c* of Fig. 2 represents the desired attenuation characteristic for the high pass directional filter such as has heretofore been employed to transmit with substantially uniform small attenuation all frequencies comprised within the upper group of frequencies and to greatly attenuate all frequencies below a definite limit. Similarly, the curve *a'*—*c'* of Fig. 2 represents the desired attenuation characteristic for the low pass directional filter designed to transmit with substantially negligible attenuation all frequencies comprised within the lower group of frequencies and to greatly attenuate all frequencies above a definite limit.

High pass filters having a characteristic

similar to that represented by the curve $a-c$ have heretofore been employed in the positions occupied by filters HPIF and HPOF of Fig. 1, while low pass filters having a characteristic similar to that represented by the curve $a'-c'$ have been employed in the positions occupied by filters LPIF and LPOF. High and low pass filters of this type are described in connection with Fig. 10 of an article entitled "Carrier current telephony and telegraphy" by Messrs. Col-pitts and Blackwell, published in the Transactions of the American Institute of Electrical Engineers, vol. 40, 1921.

15 In order to secure characteristics $b'-c'$ and $b-c$ for the circuits at the repeater points to equalize the over-all attenuation of the line and the repeater circuits, it has been the practice to insert in circuit with the grouping filters attenuation equalizer networks which gave a gradual discrimination against the lower frequencies and in favor of the higher throughout the range of each grouping filter.

20 25 In the case of the high-pass filter this meant that the filter was designed to give a sharp cut-off, which was to a great extent nullified by the equalizer network since the latter caused the total characteristic to assume a less abrupt form ($b-c$) than the filter characteristic ($a-c$) alone. The realization of this effect led to the discovery that the characteristic $b-c$ could be directly realized to a good approximation by a proper design of the high-pass filter alone, thus dispensing with the extra network heretofore employed for giving variable attenuation throughout the higher group. Not only is this extra network dispensed with 30 but it happens that the high-pass filter itself designed in accordance with the invention can be more cheaply constructed than the high-pass filter heretofore employed.

35 40 Fig. 3 shows the schematic of the high-pass filter of known type which is suitable for the high-pass filter as heretofore used and by proper design of its individual parts is also suitable for use in practising the invention. The curves d and e of Fig. 4 show typical (computed) characteristics of this filter when different values of

$$Q = 2\pi \frac{fL}{R}$$

45 50 55 are used for the inductances, f being frequency, L inductance and R resistance. Curve d is the characteristic of the type suitable for use in systems of the prior art for approximating the required characteristic $a-c$ of Fig. 2. For this curve (d) a value of $Q=150$ was used, which corre-

sponds to a very low value of resistance and means that large sized copper wire would have to be used in winding the inductances, that the iron losses must be kept low and that in general, a careful and expensive design and construction must be adopted. Curve e was obtained by using a value of $Q=10$. This curve, it will be observed, approximates the required curve $b-c$ directly, thus giving both group selectivity and attenuation equalization in the same network. Further a Q -value of 10 is so low that a much cheaper construction of filter can be used than for the curve d filter, as for example much higher resistance wire which means less copper for the same inductance.

60 65 70 75 Curve d was computed for a cut-off frequency of 14,500 cycles per second, while curve e was computed for a cut-off of 14,000 cycles per second.

80 85 The elements herein shown and described as well as the numerical values that have been given should be considered as merely illustrative of the invention, but are not to be construed as limiting the invention which, of course, is susceptible of various other modifications and adaptations.

85 90 What is claimed is:

1. In a wave transmission system in which the waves of higher frequencies in traversing the system are attenuated to a greater extent than those of lower frequencies, a selective network of a high-pass filter type having its inductances constructed with a 95 relatively small value of $\frac{L}{R}$ to give the structure a gradually changing loss characteristic throughout the transmission range to compensate for the unequal attenuation of the waves by said system. 100

95 105 110 2. In a carrier wave system employing a group of channels operating at frequencies in excess of a given frequency level, a common means for selecting the waves employed in said channels and correcting for the unequal line attenuation at the different frequencies, comprising a high-pass filter having the ratio of $\frac{L}{R}$ of its inductances
